TIRE

Charles C. Custer, Akron, Ohio, assignor to The B. F. Goodrich Company, New York, N.Y., a corporation of New York

Filed Mar. 31, 1959, Ser. No. 55,276

Term of patent 14 years

(Cl. D90—20)

Fig. 1

Fig. 2

Fig. 3

Fig. 4

Fig. 1 is a front elevational view of a tire embodying my new design, it being understood that the tread portion shown is repeated throughout the circumference of the tire;

Fig. 2 is a side elevational view thereof on a reduced scale, the opposite side being substantially like the side shown;

Fig. 3 is a fragmentary transverse sectional view thereof on an enlarged scale taken on line 3—3 of Fig. 1; and

Fig. 4 is a fragmentary perspective view of the outer sidewall portion thereof on an enlarged scale.

The characteristic features of my design for the tire disclosed reside in the low central rib extending circumferentially in the central zigzag groove of the tire tread and the provision of separate tread elements in each of the pockets or recesses along the side portions

of the tire tread with the sides of the separate tread elements extending radially on the side surfaces of the tire a distance less than the side extensions of the tread ribs defining the recesses, as shown.

I claim:

The ornamental design for a tire, substantially as shown and described.
